UNITED STATES PATENT OFFICE.

VINCENT G. APPLE, OF DAYTON, OHIO.

ENGINE-STARTER.

1,231,982.

Specification of Letters Patent.

Patented July 3, 1917.

Application filed March 11, 1915. Serial No. 13,788.

To all whom it may concern:

Be it known that I, VINCENT G. APPLE, a citizen of the United States, residing at Dayton, in the county of Montgomery and State of Ohio, have invented certain new and useful Improvements in Engine-Starters, of which the following is a specification.

My invention relates to improvements in internal combustion engine starting apparatus. It comprises more particularly improvements in motor generators and transmission gearing associated therewith for interposition between the dynamo and the shaft of an internal combustion engine.

One of the objects of my invention is the provision of such a combination, wherein a large gear reduction is obtained when the dynamo acts as a motor to start the engine, and on the reversal in the direction of drive the engine drives the dynamo as a generator at the same speed.

Another object of my invention is the provision of such a device adapted for mounting at the front end of an engine and so constructed that should the electrical starting apparatus, for any reason, become disabled, a hand crank can readily be applied to the end of the dynamo shaft and the engine turned over by hand.

Still another object of my invention is the provision of such a mechanism in which the armature shaft when rotated by hand, may be conditioned so that instead of driving the engine shaft through the large gear reduction, it drives the latter at equal speed.

Other and further objects will become apparent to those skilled in the art from a consideration of the following description and drawings, wherein:

Figure 1 is an axial sectional view of my improved apparatus.

Fig. 2 is a transverse sectional view on the line 2-2 of Fig. 1.

Fig. 3 is a transverse sectional view on the line 3-3 of Fig. 1.

Fig. 4 is a front elevation of one of the transmission gears.

Fig. 5 is a transverse sectional view on the line 5-5 of Fig. 4; and

Fig. 6 is a perspective view of a clutch ring with parts broken away.

Referring to the drawings the numeral 10 indicates the front end portion of the crank case of an internal combustion engine within which rotates the engine shaft 11 supported in a bearing 12 carried by the casing. Ex-

tending outwardly from the crank case 10, and integral therewith, in the particular embodiment of my invention shown, is a dynamo casing 13, within which rotates the armature shaft 14 concentrically positioned with respect to the engine shaft 11. The front end of the dynamo casing 15 is removably secured to the main portion of the casing by means of bolts 16 and carries at its center an annular bearing 16 within which is supported the dynamo shaft. The front end of the armature shaft 14 is slidable within the inner raceway of the annular bearing 16 for a purpose which will be described. Normally it is in the position shown in Fig. 1, the coil spring 17 interposed between the inner raceway of the bearing 16 and a pin 18 extending through the outer end of the shaft 14 normally holding it at the extreme end of its movement in this direction.

A short tubular member 19 is threaded into an aperture in the end of the casing 15 forming an end abutment for the outer raceway of bearing 16 and partially inclosing the projecting end of shaft 14. A removable cap 20 covers the outer end of the tube 19. This cap when removed provides an opening for the insertion of a hand crank starter, indicated in dotted line at 21 for engagement with pin 18 for rotation of the armature shaft 14 should the electrical apparatus for any reason become disabled.

The inner end of the armature shaft 14, carried in the roller bearing 22 mounted at the center of the head or drum 23, extends beyond the bearing in the form of a crank or eccentric 24. Mounted on this eccentric or crank 24 is a pinion 25 adapted to mesh with an internal gear 26 secured on the forward end of the engine shaft 11. A roller bearing 27 is interposed between the eccentric 24 and the wobbling pinion 25.

The pinion and the internal gear form the well known type of eccentric reduction gearing in which the wobbling or oscillating movement of the pinion through the instrumentality of the eccentric, the pinion being held from rotation, causes the rotation of the internal gear at a very low rate of speed as compared with that of the drive shaft, the ratio depending on the number of teeth in the two gears.

For the purpose of holding the floating pinion from rotation when power is to be transmitted I provide two pawls 28 and 29

having projecting pins 30—30 upon which they are pivoted. These pins extend through diametrically opposite holes in the pinion 25 and are held therein by means of the pin 5 31—31.

As shown more clearly in Fig. 2 it will be noted that the outer ends of these pawls project in the form of fingers 32 adapted to engage with the pockets 53 formed in the 10 inner face of the abutment ring 34. This abutment ring 34 is rotatably mounted within the bored out hub 35 projecting inwardly from the head 23. Rotation of this 15 abutment ring is normally prevented by means of a brake band 36 which encircles the same and is held under tension by means of the spring clamp indicated in general by the numeral 37. An annular disk 38 overlies the outer end of the brake band 36 and 20 abutment ring 34 to prevent the brake band from slipping off. Arcuate projections 39 spaced away from the brake band have the ring 38 secured thereto by the bolt 39'. The lugs 40—40 of the spring clamp 37 are positioned between two of the projections 39 25 and thus hold the brake band from rotation.

Within the space occupied by the pawls 28 and 29 in the same transverse plane is positioned a ring 41, the outer surface of 30 which is adapted to be frictionally gripped by means of the cam shaped inner faces 42, 43 of the pawls 28 and 29 when the outer weighted ends 44—44 fly outwardly under centrifugal action.

As shown in Fig. 6 an annular hub 45 extends inwardly from one end of the ring 41 and is provided with diametrically opposite slots 46. These slots are engaged normally 35 when the armature is in the position shown 40 in Fig. 1 by the pin 47 which projects transversely through an opening in the armature shaft 14.

The inner forward end of the pinion 25 is provided with ratchet teeth 47 as illustrated in Figs. 4 and 5, so that when the armature shaft is moved axially and inwardly 45 against the spring 17 the pin 47 will disengage itself from the slots 46—46 in the ring 41 and move into engagement with the 50 ratchet teeth 47 of the wobbling pinion.

The operation of the device is as follows.

When the armature is rotated for the purpose of starting the internal combustion engine the eccentric hub 24 wobbles the externally toothed pinion 25, tending to rotate the same in a counter-clockwise direction, looking at Fig. 2. Rotation of the pinion in this direction is prevented by engagement of the fingers 32—32 on the pawls 28, 55 29 with the pockets 33 on the abutment ring 34. As a result the internally toothed gear 26 is slowly rotated in an opposite direction as indicated by the arrow, thus providing initial rotation of the engine shaft 60 sufficient to cause it to take up its cycle of 65

operation. The instant the speed of the engine shaft exceeds that at which it is driven by the armature shaft the internal gear 26 will tend to drag the pinion around with it in the same direction, disengaging the pawls 70 from their pockets 33. As the speed increases the weighted ends 44—44 of the pawls will fly outwardly under centrifugal action, clamping the eccentric portions 42, 43 thereof against the periphery 75 of the ring 41 thus providing a direct 1 to 1 drive through the slots 46, 46, and the pin 47 to the armature shaft. The dynamo electric machine then serves as a generator for charging the battery, lighting the lamps, 80 etc.

The clamp 37 is adjustable so as to provide sufficient brake friction for preventing rotation of the abutment ring 34 when starting the engine but insufficient to hold the 85 same should the engine back fire, thus acting as a safety device and prevent damage to any of the parts in such event.

I have also provided in connection with this apparatus means for rotating the engine shaft from the armature shaft at an equal speed should the electrical apparatus become disabled and it becomes desirable to start the engine by hand. By removing the end cap 20 the hand crank 21 may be 90 inserted over the end of the armature shaft 14, its ratchet teeth engaging with the pin 18 and by moving the same endwise against the pressure of the spring 17, the pin 47 will disengage itself from the slots 46—46 100 of the friction ring and engage with the ratchet teeth 47 on the wobbling pinion. By thus positively rotating the wobbling pinion with the armature shaft in a clockwise direction as seen in Fig. 2 the pawls are 105 freed from the pockets and the internal gear is dragged around with the pinion at the same speed. As soon as pressure is released from the hand crank the spring 17 automatically breaks this connection and moves the 110 pin 47 into engagement with the slots 46—46, reestablishing the previously described relationship.

Having described my invention, what I claim is:

The combination of a driving shaft and a driven shaft, a crank pin on the driving shaft, an internally toothed gear secured to the driven shaft, an externally toothed gear rotatably mounted on the crank pin, a 120 friction wheel connected with the crank pin, a fixed member having pockets therein, a pawl pivoted on the externally toothed gear and having a portion adapted to be received by the pocket in the fixed member to prevent backward rotation of the externally toothed gear whereby a rotation of the driving shaft causes a rotation of the driven shaft at a reduced speed, means on the pawl 125 for engaging with the friction wheel when 130

- the driven shaft exceeds a predetermined speed, and means for either rotatably connecting the driving shaft directly to the externally toothed gear to drive the latter therefrom or for connecting the driving shaft to the friction wheel to be driven therefrom.

In testimony whereof I hereunto set my hand in the presence of two subscribing witnesses.

VINCENT G. APPLE.
